UNITED STATES PATENT OFFICE

JOHN E. STANLEY, OF DES MOINES, IOWA, ASSIGNOR, BY DIRECT AND MESNE ASSIGNMENTS, TO G. H. HUTTONLOCHER AND J. S. GILCREST, OF SAME PLACE.

INCUBATOR.

SPECIFICATION forming part of Letters Patent No. 530,907, dated December 11, 1894.

Application filed July 23, 1892. Renewed August 30, 1894. Serial No. 521,754. (No model.)

To all whom it may concern:

Be it known that I, JOHN E. STANLEY, a citizen of the United States, residing at Des Moines, in the county of Polk and State of Iowa, have invented a new and useful Incubator, of which the following is a specification.

The object of my invention is first, to provide an incubator in which the case, ventilating tubes, water tanks and lamps are so arranged as to be readily accessible, to occupy a minimum of floor space and to maintain an approximately equal temperature throughout all portions of the interior thereof.

15 A further object of my invention is to arrange the egg containing drawers within the incubator in such a manner that any one of them may be drawn out independently of the others and which are so constructed and arranged within the incubator as to allow a thorough circulation of air and heat around all of its sides.

20 A further object of my invention is to provide an egg drawer in which all of the cases may be automatically turned at the same time and which presents a smooth top surface which will not interfere with the motions of young chicks when hatched.

25 A further object is to prevent the accumulation of inflammable gases within the oil tank of the incubator lamp to preclude the possibility of explosions of the lamp thereby allowing the lamp to be filled while lighted.

30 My invention consists further in the construction, arrangement and combination of certain other parts of the machine as hereinafter set forth, pointed out in my claims and illustrated in the accompanying drawings, in which—

35 Figure 1 is a perspective view of a complete incubator. Fig. 2 is a vertical, longitudinal, sectional view through the same. Fig. 3 is a transverse sectional view of the complete machine. Fig. 4 is an enlarged, detail plan view of a portion of one of the egg containing drawers. Fig. 5 is a sectional view of the same. Fig. 6 is an enlarged, detail, plan view of a modified form of egg containing drawers. Fig. 7 is a sectional view of the same. Fig. 8 is an enlarged, detail view of

the tubes for admitting thermometers into the egg drawers.

Referring to the accompanying drawings, I employ the reference letter A to designate the outside casing of the machine, and A² the inner case at some distance therefrom. The space thus formed is filled with a non-conductor of heat, such as saw dust, charcoal, &c. The doors which provide access to the interior of the machine are also composed of an outer casing B and an inner casing B², to produce the space between them being also filled with a non-conductor of heat. The top of this door is preferably inclined and its sides and top provided with a flange B³ to provide an airtight joint between the door and casing and the said doors are located at opposite ends of the machine and are of a size approximately equaling the transverse area.

B⁴ designates strips extending vertically and secured to the sides of the interior of the incubator, and B⁵ are tracks extending horizontally and longitudinally of the casing, and adapted to support the egg containing drawers and allow them to slide thereupon. This arrangement it will be seen will provide a space between the interior of the incubator and the egg containing drawers, for the circulation of air.

Extended through the central portion of the machine are wire nets C C in proximity to the ends of the egg containing drawers when placed therein, and C² are pipes extending through the space between the said wire nets, to the bottom of the incubator to the approximate top of the interior of the incubator, and C³ is a continuation of the pipes extending through the top of the casing.

C⁴ are ventilating tubes located at the approximately central portions of each of the upper egg drawers and extended through the casing above them. By reason of the tubes C² being extended in proximity to the top of the interior of the incubator the heat is drawn from the top faster than the bottom thereof, and as heat ascends it will be obvious that this will aid in maintaining an even temperature in the machine by drawing the heated air from its top.

D designates water tanks which are located

on the bottom of the interior of the incubator and are of such a size as to occupy the entire bottom with the exception of the opening between the wire nets C C.

5 D² is a hot air conducting pipe which extends upwardly through the bottom of the incubator into the tank D and coiled within the said tank and extended through the side of the incubator and then upwardly. This pipe is 10 preferably protected between the water tank and its lower end, by means of a water containing jacket D³ which communicates with the said tank and encircles the pipe D² where it contacts with the casing, to protect it from 15 the heat. Fixed to this pipe D² at a point adjacent to its lower end is a pipe D⁴ upon which is mounted mechanism whereby the amount of heat admitted into the incubator may be regulated, by means of a thermostatic 20 bar, located within the incubator.

Means are provided for admitting thermometers through the casing into proximity to the egg drawers from the outside of the machine as follows:

25 J designates tubes extended through the casing at points adjacent to the egg drawers. J² are thermometers fixed to rods J³ which in turn are connected with the stoppers J⁴. By this arrangement the temperature of either 30 of the egg drawers may be seen without opening the incubator door, by drawing the thermometers through the tubes by means of its handle.

K designates a lamp of common form placed 35 beneath the end of the pipe D² to supply heat to the incubator.

K² designates a tube inserted in the top of the oil containing chamber of the lamp, and leading outwardly therefrom. This tube K² 40 is for the purpose of allowing inflammable gases generated in the said chamber by the heat of the lamp to escape, thereby adapting the lamp to be filled when burning.

L designates the egg containing drawers 45 which are adapted to slide upon the tracks B⁵ and which are composed of longitudinal slats L² with spaces between them to allow the free circulation of air.

L³ designates a drawer within the drawer L 50 and resting upon its bottom. Its width is such as to allow it to slide within the drawer L and it is slightly shorter than the said drawer, to allow a slight longitudinal movement therein. Formed within this drawer L² are a plurality 55 of perforations which are of such a size and shape as to admit an egg and allow it to rest upon the drawer L and at the same time prevent it from passing through the said perforations. The modified inner drawer is formed

60 of heavy paper N supported by longitudinal strips N². This latter form of egg drawer may be more cheaply constructed than the former one and the paper serves to prevent shocks and jars to the incubator frame, from injur- 65 ing or retarding the growth of embryo chicks.

O designates a plurality of pans for containing water to thereby supply moisture to the

eggs, by evaporation. These pans rest upon the tank D and extend longitudinally thereof.

Having thus described the construction and 70 function of each separate operative part of the incubator in turn, what I claim as my invention, and desire to secure by Letters Patent of the United States, is—

1. In an incubator, the combination of a 75 suitable protecting case, having a door at each end, a plurality of tracks leading from both ends to the interior and arranged one above the other, a wire netting or its equivalent fixed to the interior of the incubator and ex- 80 tended around the sides of each end portion, at a slight distance therefrom and through the central portion thereof to produce a chamber for the circulation of air around the drawers, and to prevent the young chicks from 85 falling off, a water tank placed on the bottom of each end of the device, means for heating said water tank, and ventilating tubes ex- 90 tending from the bottom of the incubator upwardly to the approximate top portion of the interior of the incubator, and ventilating tubes extended through the top of the incubator, substantially in the manner set forth and for the purposes stated.

2. In an incubator, the combination of a 95 suitable casing having a door at each end, a plurality of tracks leading from both ends to the interior and arranged one above the other, a wire netting or its equivalent fixed to the interior of the incubator and extended 100 around the sides of each end portion, at a slight distance therefrom and through the central portion thereof to produce a chamber for the circulation of air around the drawers, and to prevent the young chicks from falling 105 off, a water tank placed on the bottom of each end of the device, a pipe coiled within each tank and having its one end extending through the bottom of the incubator and its other end through the side and then upwardly, 110 a pipe extending upwardly through the bottom of the incubator into proximity to the top 115 of its interior between the central wire nettings and a plurality of ventilating tubes extended through the top of the incubator, and means for closing the said tubes, substantially in the manner set forth and for the purposes stated.

3. In an incubator the combination of the following elements, to wit: a casing composed 120 of an outer wall A and an inner wall A² with a nonconductor of heat between them, the doors at each end thereof composed of the parts B and B² and having the flange B³, the vertical strips B⁴ secured to the inner walls 125 of the incubator for the purposes stated, the tracks B⁵ secured to the said vertical strips and extended longitudinally of the incubator, the wire netting C extending around the sides 130 and across the central portion of each end as set forth, the ventilating tubes C² extending through the bottom portion of the casing, the tubes C³ and C⁴ extending through the top of the same, the water tanks D resting on the

bottom of the interior of the incubator, the coiled pipes D² within said tanks and opening below the casing to admit heat to the tanks, the water jackets D³ surrounding portions of said pipes and the lamps K all arranged and combined substantially as and for the purposes stated.

4. An improved incubator composed of the following elements; a suitable double walled casing having a door at each end, a plurality of tracks extending from the ends to the central portion of the incubator and arranged one above the other, suitable ventilating tubes to supply fresh air into the incubator, a hot water tank located in the bottom of each end, a coiled pipe within each tank reaching to the bottom of the incubator through the tank and out at its side, a lamp beneath the lower end of each of the said pipes, a plurality of egg drawers arranged to be placed in each end and located above the other, means substantially as shown for automatically regulating the heat of the interior of the incubator, and the tubes extended through the sides of the incubator whereby a thermometer may be admitted into the egg drawers, arranged and combined substantially as set forth.

5. An improved incubator comprising the casing composed of the outer portion A and the inner portion A² with a nonconducting material between them, a door at each end of said casing composed of the parts B and B² and having a flange B³, the wire nettings C C, the ventilating tubes C² C³ and C⁴, the tank D having the coiled pipe D² arranged therein,

the water containing jacket D³ surrounding portions of the pipe D², the branch pipe D⁴, the damper H³ adapted to enter the pipe D² and cut off the supply of heat in the incubator, and means for operating the said damper, a plurality of tubes J extended through the sides of the incubator in proximity to each egg drawer and a thermometer J² fixed to the rod J³ and a stopper J⁴ adapted to be extended through the tubes J into the incubator, a lamp K having a tube K² arranged therein as set forth, an egg containing drawer composed of the part L and the part L² having perforations L³ formed therein, all arranged and combined substantially in the manner set forth and for the purposes stated.

6. In an incubator having doors for the admission of egg containing drawers at each of its ends, the combination of a plurality of tracks arranged one above the other, adapted to support egg containing drawers and extended from each end toward the center of the incubator, and wire nettings fixed to the interior of the incubator and extending around the sides and inner ends of the egg containing drawers at a slight distance from the sides of the incubator to provide a space for the circulation of air and heat around the egg containing drawers and to prevent young chicks from falling off of the egg drawers, substantially as set forth.
